ENGINE SOUNDPROOFING

Harry Najimian, Jr., Lake Bluff, Ill., assignor to Outboard Marine Corporation, Waukegan, Ill., a corporation of Delaware

Filed May 1, 1962, Ser. No. 191,486
6 Claims. (Cl. 115—34)

This invention relates generally to reduction of the noise level associated with operation of a boat engine or motor. The invention specifically relates to boats having engines mounted in the boat adjacent the transom and involves the use of a housing which is fabricated to prevent transmission therethrough of sound waves and which is disposed in substantially enclosing relation to the engine, thereby reducing the noise level in the boat in the areas adjacent to, and immediately forward of, the engine. Such fabrication involves the use of a housing including a rigid outer shell, which is preferably curvilinear throughout, and a sound absorbing lining on the interior of the shell.

The invention also contemplates cushioned mounting of the housing on the boat frame to prevent transmission of vibration therebetween, and the removability of at least a part of the housing from its mounting so as to facilitate servicing of the engine.

In general, the principal object of the invention is the provision of an arrangement for substantially reducing the operating noise level of an engine mounted in a boat, and in particular of an engine mounted adjacent to the transom of a boat. Other objects of the invention will become apparent by reference to the following description and the accompanying drawings of one embodiment of the invention.

In the drawings:

FIGURE 1 is a partially broken away and partially exploded view of a sound reducing arrangement embodying various of the features of the invention;

FIGURE 2 is an enlarged view, partially in section, of a portion of the arrangement shown in FIGURE 1; and

FIGURE 3 is an enlarged perspective view of the manner in which one of the arms of the engine block extends through the sound reducing housing.

The boat 11, shown fragmentarily in FIGURE 1, includes support means or a frame 13 including, at the stern, a transom 15 which is either attached to or constitutes a part of a vertical boat frame portion 17. The vertical boat frame portion 17 serves to support, at least in part, the weight of an engine 19 and an associated propulsion unit (not shown).

Various types of engines can be employed and various arrangements are usable for supporting the engine on the boat frame. In the preferred construction, the engine is entirely supported by attachment to the boat frame 13 in the immediate region of the transom 15 and extends forwardly, being otherwise generally unsupported. More particularly, the engine block 21 has cast therewith four arms 23, two of which are secured to a horizontal member 18 of the vertical frame portion 17, and two of which are secured to the vertically extending leg 20 of a bracket 22 which is secured to a bottom portion 24 of the boat frame which extends from and is disposed immediately adjacent the transom 15. The upstanding leg 20 can be considered a part of the vertical frame portion 17. Preferably, the connection of each of the mounting arms 23 to the boat frame 13 includes elastomeric pads or cushions 25 (see FIGURE 2) which exclude or dampen transmission of vibration from the engine 19 to the boat frame 13.

Reduction of the noise level associated with the operation of the engine 19 is obtained by substantially enclosing the engine in a housing 29 which is supported by the boat frame 13 in spaced relation to the engine 19 and is

2

fabricated to at least partially absorb sound waves emitted by the engine and to prevent transmission therethrough of the non-absorbed sound waves. More particularly, the housing 29 includes an outer shell 31 which is relatively very rigid to minimize sympathetic vibration, thereby preventing actuation of the shell as a sounding board. In this connection, sounding board action can be minimized by fabricating the housing in an overall curvilinear formation, i.e., with a minimum of flat or planar surfaces. Thus, in the disclosed construction, the housing is generally of cylindrical form with a forward dome shaped end. In addition, the housing 29 includes an inner lining of sound absorbing material 33, such as fiberglass or foamed polyurethane.

The housing 29 is preferably supported by the transom 15 or vertical frame portion 17 for forward extension in spaced enclosing relation to the engine, and is preferably constructed to afford removal of at least a part thereof to provide access to the engine 19 for maintenance, etc. In this regard, the housing 29 includes a rearwardly located, forwardly open part or portion 35 which is mounted on the transom 15 of the vertical frame portion 17, and a forwardly located, rearwardly open part or portion 37 which can be releasably assembled by suitable clips or fastening means 36 to the rearward part 35.

In order to prevent the escape of undesired sound waves from the housing when the parts 35 and 37 are in assembled condition, the mating margins are provided with co-operating sealing means for providing a generally tight joint. Since it is also desirable to prevent transmission of vibration from either housing section to the other, the sections are desirably isolated by making the sealing means elastomeric. More particularly, the rearward part 35 includes a resilient ring or member 41 of rubber, or like material, while the forward part 37 includes a peripheral slot or seat 43 into which the member 41 is received in generally tight engagement. The resulting relatively tight joint between the housing parts 35 and 37 also serves to retain the forward part in proper, spaced position to the engine.

The housing 29 is desirably insulated from the boat frame 13 to prevent the transmission therebetween of any vibration. Thus, in the preferred construction, the rearward part 35 of the housing is mounted on the transom 15 by means including an elastomeric ring assembly 45 (see FIGURE 2). In the preferred construction, the elastomeric ring includes two metallic rings 51 and 53, and an annular elastomeric pad 55 bonded to each of the metallic rings 51 and 53 to provide a concentric assembly of sandwich-type construction. Both rings are tapped to receive a series of mounting screws 57 providing attachment of the elastomeric ring assembly 45 to the transom 15 and to the rearward portion 35 of the housing or motor cover 29. When thus assembled, the annular elastomeric pad 55 between the rings 51 and 53 isolates the rings from each other, thereby isolating the housing 29 from the transom 15. In the case of stern drive units in which the propulsion unit is carried rearwardly of the transom 17, it is also preferred to seal the opening in the transom to prevent the escape of sound transmitting air waves. Various arrangements can be used, as for instance, a canvas connection 46 can be employed.

Although the rearward part 35 of the housing 29 is apertured to permit passage therethrough of the mounting arms 23, escape of sound transmitting air waves through the apertures and the transmission of vibration from the engine arms 23 to the housing 29 are precluded by the use of elastomeric grommets or sealing means 47 engaging both the rearward housing part 35 and the arms 23.

Although the disclosed housing has been described and shown as mounted on a vertical portion of the frame, the

housing can be partially mounted on the bottom as well as on the vertical portion of the boat frame. Additionally, the housing could be in other than a cylindrical form.

Various other of the connections normally associated with an internal combustion engine, such as for instance, electrically supply and fuel supply, can also be passed through the housing in grommeted openings. Air intake and exhaust can be provided either through the housing or through the transom, whichever is preferred in a given instance. Flexible grommets are desirably employed in association with such air intake and exhaust conduits to prevent the passage of sound transmitting air waves and to insulate the housing or transom from vibration associated with the engine.

Various of the features of the invention are set forth in the following claims.

What is claimed is:

1. The combination of a boat frame having a vertical portion at the stern thereof, a rigid housing which is of generally curvilinear configuration throughout and which has a sound absorbing padding applied to the inner surface thereof and including a rearwardly located, forwardly open portion extending from said vertical frame portion, a forwardly located portion closed at its forward end and open at its rearward end, co-operating sealing means including a resilient member on one of said housing portions and a seat on the other of said housing portions, and means for releasably assembling said housing portions to each other with said resilient member engaged with said seat to prevent the passage of sound carrying air waves through the connection of said first and second housing portions, means mounting said rearwardly located housing portion to said vertical frame portion including elastomeric material for preventing the transmission of vibration from said boat frame to said housing, an engine located within and in spaced relation to said housing, means mounting said engine, at least in part, to said vertical frame portion and including at least one arm extending through said housing, and elastomeric means engaging said housing and said arm for substantially preventing the transmission therebetween of vibration or the passage therebetween of sound carrying air waves.

2. A mounting in a boat for an internal combustion engine comprising vertically extending support means, a horizontally elongated engine wholly supported, adjacent one of its ends, on said support means, and a sound-proofing enclosure supported on said support means in horizontally extending relation to said support means and in enclosing relation to said engine, said enclosure being free of connection with said engine.

3. The combination in a boat of support means including a vertically extending support, a horizontally elongated engine, means mounting said engine solely adjacent one of its ends on said support and including means for excluding the transmission of vibration between said engine and said support, a sound-proofing enclosure, and means mounting said enclosure on said support means in horizontally extending relation to said support and in enclosing relation to and free of contact with said engine, said means mounting said enclosure including means for

excluding the transmission of vibration between said enclosure and said support means.

4. The combination in a boat of support means including a vertically extending support, a horizontally elongated engine, means mounting said engine solely adjacent one of its ends on said support means adjacent to said vertically extending support, said engine mounting means including means for excluding the transmission of vibration between said engine and said support means, a sound-proofing enclosure, and means mounting said enclosure on said vertically extending support and in enclosing relation to and free of contact with said engine, said means mounting said enclosure including means for excluding the transmission of vibration between said enclosure and said supports.

5. The combination in a boat of support means including a generally vertical portion adjacent the stern of said boat, an internal combustion engine mounted on said support means immediately adjacent to and at least partially on said vertical portion and in otherwise unsupported forwardly extending relation to said vertical portion, and a rigid housing having an exterior of generally curvilinear configuration throughout, and mounted on said vertical portion of said support means in generally enclosing, spaced relation to said engine, said housing having its inner surface lined with a sound absorbing material and being mounted on said vertical portion of said support means by means for excluding the transmission of vibration therebetween.

6. The combination in a boat of support means including a generally vertical portion adjacent the stern of said boat, an internal combustion engine mounted on said support means immediately adjacent to and at least partially on said vertical portion and in otherwise unsupported forwardly extending relation to said vertical portion, and a rigid housing having an exterior of generally curvilinear configuration throughout, having its inner surface lined with a sound absorbing material, extending in generally enclosing, spaced relation to said engine, and including first and second parts and means releasably connecting said first and second parts, one of said parts having thereon a sealing member of resilient material and the other of said parts having a seat for receiving said sealing member, thereby preventing the passage of sound transmitting air waves through the connection between said housing parts, said first part being mounted on said vertical portion on said support means by means for excluding the transmission of vibration therebetween.
